UNITED STATES PATENT OFFICE.

GEORGE L. FREEMAN, OF TICONDEROGA, NEW YORK, ASSIGNOR OF ONE-HALF TO
RICHARD F. HAYES, OF TICONDEROGA, NEW YORK.

SPARK-PLUG.

1,230,287.

Specification of Letters Patent. Patented June 19, 1917.

Application filed February 4, 1916. Serial No. 76,210.

To all whom it may concern:

Be it known that I, GEORGE L. FREEMAN, a citizen of the United States, residing at Ticonderoga, in the county of Essex and 5 State of New York, have invented certain new and useful Improvements in Spark-Plugs, of which the following is a specification.

This invention relates to certain new 10 and useful improvements in ignition devices for internal combustion engines and resides more especially in the production of a spark plug which can be readily affixed to any well known type of engine.

15 In practice it has been found that after using a spark plug in the ordinary type of engine where it is exposed to the products of combustion, an appreciable amount of carbon is soon deposited upon the points or between the surfaces over which the spark jumps, and the efficiency of the motor is materially reduced, sometimes to the extent of complete inoperativeness, until these 20 plugs have been removed, the points carefully cleaned, and the plug again positioned in the motor.

25 Certain attempts to remedy this difficulty have been made and shields or protecting guards have been arranged about the spark points so as to deflect the products of combustion and prevent the collection of oil and carbon.

30 To some extent, devices of this character have added to the efficiency of the motor for a period, but after continued usage the efficiency is again reduced and the removing and cleaning of the plugs are required at frequent intervals.

35 An object of the present invention is to 40 overcome these existing difficulties, and provide a spark plug in which the accumulation of oil and carbon is prevented by means peculiarly a part of the sparking terminals or points.

45 Another object of the present invention is 50 the production of a spark plug including, in combination, a movable terminal, supported and positioned upon the lower end of the plug and adapted to coact with an opposing stationary terminal for preventing the depositing of oil, carbon and other extraneous foreign matters therebetween.

55 With these and other objects in view, the invention further consists in the combination and arrangement of parts adapted to ex-

clude all carbon and oil, and add materially to the economic value of the plug for general use, as will more fully hereinafter appear.

In the drawings which show by way of illustration an embodiment of my invention, 60 and in which similar reference characters designate like parts—

Figure 1 is a side elevation of my improved spark plug.

Fig. 2 is a vertical sectional view thereof. 65

Fig. 3 is a detail perspective view of the tubular washer adapted to space the movable terminal and seal the space around the central stem or rod against the entrance of oil and carbon, and

70 Fig. 4 is a similar view of the movable terminal.

Referring to the drawings, my present invention includes among other things an outer shell 1 provided with the usual screw threads 2 for positioning the plug in the cylinder of a motor (not shown). This shell has near the upper end thereof flattened or hexagonal surfaces 3, by means of which it can be readily positioned and securely adjusted in the cylinder of a motor. 75

80 An insulating body portion 4 is arranged within the shell 1, and is provided with the usual tapering upper portion 5, as shown. The material from which this body portion 85

4 is made is preferably porcelain, but it may be of other substances or compositions possessing the necessary characteristics to permit of the proper operation of the plug. This body portion 4 is provided with shoulders 6, as shown in Fig. 1, against which a suitable packing or sealing material 7 is inserted. This packing material 7 is preferably arranged near the top and bottom, respectively, of the outer shell 1, and is arranged to adapt itself to all crevices and openings by means of the nut 8 screw-threaded into the upper portion of the shell, as will be readily understood. By this construction it will be readily seen that the body portion is completely sealed within the shell 1, and protected against the entrance of oil and carbon. 90

95 The body portion 4 is provided with an opening 9 extending the length thereof, and arranged to receive a rod or stem 10 threaded at the upper end as at 11 and threaded at the lower end as at 12. A head 13 is provided on the rod 10 and serves to hold the movable terminal 14 in position. The usual 105

110

cap screw 15 and locking nut 16 are provided on the upper end of the rod and bear against the usual washers 17, between or around any of which of the above-mentioned 5 parts, the terminal end of the conductor can be affixed in any well known manner.

The movable terminal 14 is loosely mounted upon the rod or stem 10, and is provided with a beveled upper surface 18. By this 10 construction it will be readily seen that oil and other substances will be deflected and prevented from accumulating on the terminal. Suitable projections 19 extend from the said terminal and are adapted to coat 15 with an annular stationary terminal surface provided on the under-side of the sleeve 20 of the outer shell 1. As shown in the drawings this terminal surface on the sleeve 20 is annular, but I do not limit myself to such 20 shape, as various other contours can be provided.

A tubular threaded washer 21 is interposed between the movable terminal 14 and the lower end of the body portion 4 and 25 serves to confine packing 22 about the rod or stem 10 and prevent the entrance of oil, carbon or the products of combustion within the body portion.

This washer 21 is constructed with a head 30 23, between which and the upper beveled surface of the movable terminal 14, a space is preferably provided. This space can be regulated as occasions require.

As hereinbefore mentioned, this terminal 35 14 is movable and free to rotate about the rod or stem 10. In the operation of the device it will be apparent that the successive sparking between the movable and stationary terminals will produce a vibratory action 40 upon the movable terminal 14, which is sufficient to dislodge the products of combustion—oil and other substances as they encircle the lower end of the spark plug immediately following the explosion stroke of the

piston. The force of the explosion and general vibratory action of the motor will also tend to move this terminal member 14 and assist in the removal of all carbon between the movable and stationary terminals, as well as in and around the washer 21 and the 50 protruding end of the body portion 4.

From the foregoing it will be obvious that I have produced an efficient and substantially self-cleaning spark plug capable of long and reliable service in motors of the internal combustion type. 55

Having thus described my invention what I claim and desire to secure by Letters Patent is:

1. A spark plug of the character described 60 including in combination a stationary terminal, an adjustable rod extending through said stationary terminal, a movable terminal carried by said rod, said movable terminal comprising a disk having a cone-shaped upper surface formed to slope downwardly toward the edge of said disk from the center, and upwardly extending sparking points arranged near the edge of the said cone-shaped upper surface and spaced 65 from the stationary terminal.

2. A spark plug of the character described including in combination a stationary terminal, a rod extending through said stationary terminal, a head formed on the lower 75 end of said rod, an adjustable washer threaded on said rod and spaced from the aforesaid head, and a movable terminal loosely mounted between the said washer and head, said movable terminal having a sloping upper surface and sparking points spaced from the stationary terminal. 80

In testimony whereof I affix my signature in presence of two witnesses.

GEORGE L. FREEMAN.
